UNITED STATES PATENT OFFICE.

ERNEST GOTHLBERG, OF JERSEY CITY, NEW JERSEY.

COMBINED SOCKET-COVER AND SHADE-HOLDER.

SPECIFICATION forming part of Letters Patent No. 727,934, dated May 12, 1903.

Application filed December 3, 1902. Serial No. 133,717. (No model.)

To all whom it may concern:

Be it known that I, ERNEST GOTHLBERG, a citizen of the United States, residing in Jersey City, in the county of Hudson and State of New Jersey, have invented certain new and useful Improvements in a Combined Socket-Cover and Shade-Holder, of which the following is a specification.

This invention relates to certain improvements in combined socket-covers and shade-holders for electroliers or chandeliers, so that a more convenient and ornamental device is obtained by which access is given at all times to the lamp-socket whenever it is necessary to examine or repair the wiring of the same.

Heretofore socket-covers were permanently attached to the lamp-socket and had to be bent in backward direction, so as to get access to the socket. This backward bending of the cover in order to examine the socket and the forward bending of the same after it had been repaired was very annoying and often produced the breaking off of some of the ornamental portions of the cover.

The object of this invention is to dispense with the objections to the present socket-cover and combine the same with the shade-holder, which was heretofore made integral with the socket itself, in such a manner that the combined socket-cover and shade-holder can be readily detached at any time from the lamp-socket, so as to give convenient access to the same; and for this purpose the invention consists of a combined socket-cover and shade-holder that is formed of a bell-shaped metallic body or shell placed over the lamp-socket and provided at one end with means for attachment to the lamp-socket and at the other end with means for supporting the shade.

In the accompanying drawings, Figure 1 is a perspective view of the improved combined socket-cover and shade-holder forming the subject-matter of this invention, showing the device supporting the shade and as attached to the lamp-socket and electrolier. Fig. 2 is a vertical central section through the combined socket-cover and shade-holder, and Fig. 3 is a perspective view of my improved device shown as detached from the lamp-socket.

Similar letters of reference indicate corresponding parts.

Referring to the drawings, A represents a lamp-socket of the usual construction, which lamp-socket is provided with the usual switch, so that when the lamp B is screwed into the 55 socket the proper connection of the conducting-wires is made. The shell of the lamp-holder is attached by screws *a a* to the base or cap of the socket, which is applied to the arm of the electrolier in the usual manner. 60 The screws *a* serve at the same time for attaching the combined socket-cover and shade-holder by means of L-shaped slots *d*, which are arranged in the upper end or rim of the combined socket-cover and shade-holder, as 65 shown clearly in Fig. 3.

The combined socket-cover and shade-holder is formed of a bell-shaped metallic body or shell D, which is preferably provided with cylindrical portions or rims *d' d'*. The 70 upper contracted rim *d'* is provided at diametrically opposite points with L-shaped recesses *d*, that serve to form with the clamping-screws *a* in the end of the shell of the lamp-holder bayonet-joints, so as to permit 75 the attachment of the shade-holder to the lamp-socket by the same screws by which the lamp and socket are connected with each other. The shell D is also provided with a suitable recess K for the manipulation of the 80 key of the lamp. The shell D is placed in position on the lamp-socket by placing the L-shaped slots on the shanks of the clamping-screws *a* and then turning the same as far as permitted by the angular portion of 85 the L-shaped recesses in the rim of the shade-holder, after which the clamping-screws are tightened up, so as to firmly hold the shell D in position on the lamp-socket.

The outer or larger cylindrical rim *d'* of the 90 socket-cover D is provided at three points with the usual screws *e* for supporting the neck of the lamp-shade, said neck being provided with a concaved rim for permitting the engagement with the supporting-screws in 95 the well-known manner. At the points where the shade-supporting screws pass through the rim *d'* the rim is provided with screw-threaded collars that are soldered to the rim in the usual manner.

The metallic shell D can be made of plain sheet metal, or the shell may be ornamented

in the manner shown in Figs. 1 and 3, the ornamentation being preferably in keeping with the style and character of the electrolier in connection with which the combined socket-cover and shade-holder is to be used.

The combined socket-cover and shade-holder forms a very convenient and ornamental device for the purpose described, especially as it dispenses with the inconvenient ornamental socket-covers heretofore in use and substitutes a device that can be readily removed for examining or repairing the lamp-socket, while it forms when in position on the lamp-socket a neat and practical supporting device for the shade, not requiring any attaching device for attaching the same to the lamp-socket.

Having thus described my invention, I claim as new and desire to secure by Letters Patent—

1. The combination, with a lamp-socket, having a cap, and a shell, and exteriorly-accessible screws securing the same together, of a cover adapted to inclose said shell and to be secured by the same screws, substantially as set forth.

2. The combination, with a lamp-socket, having a cap, and a shell, and exteriorly-accessible screws securing the same together, of a cover adapted to inclose said shell and to be secured by the same screws, and means

for securing a shade to said cover, substantially as set forth.

3. The combination, with a lamp-socket, having a cap, and a shell, and exteriorly-accessible securing-screws at the circumference of the cap, of a cover adapted to inclose said shell and the circumference of said cap, and to be secured by the same screws, substantially as set forth.

4. The combination, with a lamp-socket, having a cap, and a shell below the same, and exteriorly-accessible securing-screws at the circumference of said cap, of a cover adapted to inclose said shell and the circumference of said cap, and to be secured by the same screws, and means for securing a shade to said cover, substantially as set forth.

5. The combination, with a lamp-socket, having a cap, and a shell below and within the same, and exteriorly-accessible securing-screws at the circumference of said cap, of a cover adapted to inclose said shell and the circumference of said cap and to be secured by the same screws, substantially as set forth.

In testimony that I claim the foregoing as my invention I have signed my name in presence of two subscribing witnesses.

ERNEST GOTHLBERG.
